CLAIM

The ornamental design for a gaming machine, as shown and described.

DESCRIPTION

FIG. 1 is a front, top perspective view of a gaming machine showing our new design according to a first embodiment;

FIG. 2 is a front view thereof;
FIG. 3 is a rear view thereof;
FIG. 4 is a right side view thereof;
FIG. 5 is a left side view thereof;
FIG. 6 is a top plan view thereof;
FIG. 7 is a rear, bottom perspective view thereof;
FIG. 8 is a front, top perspective view of a gaming machine showing our new design according to a second embodiment;
FIG. 9 is a front view thereof;
FIG. 10 is a rear view thereof;
FIG. 11 is a right side view thereof;
FIG. 12 is a left side view thereof;
FIG. 13 is a top plan view thereof;
FIG. 14 is a rear, bottom perspective view thereof;
FIG. 15 is a front, top perspective view of a gaming machine showing our new design according to a third embodiment;
FIG. 16 is a front view thereof;
FIG. 17 is a rear view thereof;
FIG. 18 is a right side view thereof;
FIG. 19 is a left side view thereof;

FIG. 20 is a top plan view thereof;
FIG. 21 is a rear, bottom perspective view thereof;
FIG. 22 is a front, top perspective view of a gaming machine showing our new design according to a fourth embodiment;
FIG. 23 is a front view thereof;
FIG. 24 is a rear view thereof;
FIG. 25 is a right side view thereof;
FIG. 26 is a left side view thereof;
FIG. 27 is a top plan view thereof; and,
FIG. 28 is a rear, bottom perspective view thereof.
The dashed broken lines in the figures illustrate portions of the gaming machine that form no part of the claimed design. In FIGS. 15-28, the gaming machine is shown with a symbolic break in its length. The pairs of adjacently-spaced dot-dot-dash broken lines in FIGS. 15-28 form no part of the claimed design. The appearance of any portions between such pairs of adjacently-spaced dot-dot-dash broken lines forms no part of the claimed design.
